Charles C. Meutsch
By Jno. L. Elliott, Atty.

UNITED STATES PATENT OFFICE.

CHARLES C. MEUTSCH, OF CHICAGO, ILLINOIS.

UPHOLSTERED CURVED ARM, BACK, SEAT, ETC.

1.414,824.

Specification of Letters Patent.

Patented May 2, 1922.

Application filed October 17, 1918. Serial No. 258,534.

To all whom it may concern:

Be it known that I, CHARLES C. MEUTSCH, citizen of the United States, and resident of the city of Chicago, in the county of Cook and State of Illinois, have invented certain new and useful Improvements in Upholstered Curved Arms. Backs. Seats, Etc., of which the following is a full, clear, and exact specification.

- 10 This invention relates to improvements in upholstered curved arms, backs and seats for sofas and chairs and also bolsters, cushioned by means of coiled springs seated close together at their inner ends following the curvature of a frame or other form and secured at their outer ends to a cover, usually burlap, providing a foundation for a stuffing for tow, moss or hair as may be underlying an upholstery fabric.
- 15 20 Heretofore the use of coiled springs for upholstered arms, backs, seats and bolsters, has been confined to either those of the hour-glass or straight cylindrical type so seated and therefore unavoidably diverging outwardly and consequently separated at their outer ends so widely, that following repeated compressions of the springs, folds are produced in their cover and in the stuffing, and projected inwardly between the springs
- 25 30 exposing the cover to a frictional wearing contact therewith materially reducing the normal resiliency and compressibility of the springs and in a short time producing not only unsightly depressions and humps in the surface of upholstering, but discomfort to the occupant.
- 35 The prime object of my invention broadly stated, is to provide the upholstered curved arms, backs and seats for sofas and chairs and also bolsters, with coiled springs so formed and arranged that when in their operative position, and following the curved surface of the frame or other form supporting them, the sides of adjacent springs shall normally occupy parallel planes and be adapted for preventing the projection of the cover between said sides.

More specifically stated the object of my invention is to cushion these several curved upholstered structures with coiled springs having the form of a truncated cone, the sides of which are tangent to the circle and if need be, variations in the circle occupied by their several springs so that when their inner end coils are seated as heretofore in close contact, their outer ends will be likewise in contact and provide a substantially

continuous curved and unbroken surface for their cover and the layer and layers of stuffing overlying the said cover.

Another object of my invention is to provide pockets for springs so formed that they not only conform to the shape of the springs and conveniently attachable to the covering of their supporting frame, but are so constructed as to provide a plurality of openings longitudinal thereof for the convenient insertion of the springs therein to their operative position, whereby the springs and pockets may be shipped separately with minimum compactness and cost in transportation and assembled without the exercise of any particular skill or experience.

With these ends in view, my invention finds embodiment in certain features of novelty in the construction, combination, and arrangement of parts, by which the said objects and certain other objects are attained, all as hereinafter fully described with reference to the accompanying drawing and more particularly pointed out in the claims. In said drawing:

Fig. 1 is a perspective view of a sofa in which my invention finds its embodiment.

Fig. 2 is a vertical section of an arm for a chair or for a sofa.

Fig. 3 is a transverse section through and showing the adaptation of my invention to a bolster for a bed, and—

Fig. 4 is an enlarged detail perspective view of one of the coil springs and the retaining pocket therefor.

Similar characters of reference indicate the same parts in the several figures of the drawing.

Following the usual practice the frame forming the foundation consists of cross bars 5, 5 connecting end boards 6, 6 one of which is shown in Fig. 2, the edges of which as indicated at 7 are curved or of other configuration to conform to the predetermined design of the upholstered arm, back or seat which frame is covered and enclosed by a fabric secured to the edges of the end boards and provides the support for coiled springs 9, and may if desired, be stuffed with moss, tow, hair or other suitable material 8 as indicated in Fig. 2.

In carrying out my invention the coil springs 9, have the form of truncated cones 110 the smaller ends of which rest upon and are directly supported by the frame-cover 7, which springs are inwardly enclosed in a pocket preferably formed from two fabric

strips 10 and 11 crossing each other, and having flaps 12, secured to the cover 7^a by lines of stitching 13.

By forming the pockets from crossed strips, openings 14, are provided at their corners for the convenient insertion of the springs to their operative positions, their removal when injured and the substitution of other springs therefor, while at the same time such pockets operate to limit the expansion of the springs and to retain adjacent springs from physical contact with each other.

The length of these truncated springs and of their pockets may be varied to correspond with the desired curvature and depth of the upholstery, as for instance in Fig. 2 wherein the depth of the pockets toward a front side of the curvature of an arm or back, is shown to be greater than the pockets rearwardly thereof, that is to say than the distance between the inner and outer converging curves of the covering 7 and the outer covering 15 from the front to back of the structure.

By the use of coil springs of truncated form a means is not only provided for supporting their inner ends with the coils of adjacent springs in contact with each other, but for maintaining closeness of contact of other springs throughout its length and avoiding spaces heretofore occurring following the divergence of coiled springs either of the cylindrical or hour-glass type.

In Fig. 2 is illustrated a "construction" in which the fabric covering 15, extending over the outer ends of the pockets enclosed in the springs furnishes the support for a stuffing of tow, moss or hair, 16, as may be, enclosed see Fig. 1, by the outer enclosing fabric 16^a, of the finished arm or back.

When truncated cone springs for cushioning arms and backs are used in connection with coiled springs cylindrical in form for the plain surfaces of an upholstered structure, they provide a means by which it is possible and practical to maintain a substantially continuously spring surface throughout the structure, the truncated cone springs of which and the adjacent cylindrical springs operate to brace each other against lateral displacement longitudinally, and bending laterally, and whereby the compressive force applied to each of said springs is directed axially to each of them and certainly more nearly so than is possible with the use in curved arms and backs of springs of any form other than that of a truncated cone.

While I have illustrated my invention in connection with and as applied to curved arms and backs, it is here to be noted that it is applicable to the curved edges of upholstered seats and that it extends to and includes upholstered bolster construction of cylindrical form as illustrated in cross sec-

tion in Fig. 3 wherein spring containing pockets 18 having this form of a truncated cone are constructed and secured as shown in Fig. 4 to a tubular foundation of fabric 19, stuffed with tow, moss or hair 20, which 70 pockets are provided with a cover 21 adapted to form the support as in Fig. 2 for a stuffing enclosed by the upholstery, the outer fabric such as for example the fabric indicated at 16 in Fig. 1.

My invention in the use of truncated springs is as before indicated also adapted for the outer edges of seats, for sofas, and chairs when it is desirable to merge the flat top surfaces thereof into a curved form as 80 is the common practice in so called Turkish upholstery, the advantage being, that by the location of truncated springs in the position and arrangement before described, the rounded edges so formed are not only uniformly yielding, but the truncated springs operate as a stop, tending to prevent the toppling and longitudinal bending of the cylindrical springs for the flat surface adjacent thereto.

Having described my invention what I claim and desire to secure by Letters Patent is:

1. The herein described upholstered devices, comprising in combination a curved 95 supporting structure, tapering coiled springs seated thereon at their smaller end and projecting outwardly therefrom, a fabric pocket for each of said springs the opposing adjacent sides of which are in parallel planes, 100 and an enclosing cover therefor.

2. The herein described upholstered devices comprising in combination a supporting structure having a curved surface and number of coiled springs having the form of 105 truncated cones seated thereon and a covering therefor which said coiled springs vary in length to correspond with the distance between the support and their outer covering.

3. The herein described upholstered devices comprising in combination a structural form having a curved surface from end to end and number of truncated coiled springs, the truncated ends of which are seated thereon with the bottom coils of adjacent springs substantially in contact with each other and with their outwardly diverging sides located in parallel planes, pockets for each of said springs and a fabric cover for and surrounding the surface of said springs and secured to the supporting frame.

In witness whereof, I have hereunto set my hand and affixed my seal, this 5th day of October, A. D. 1918.

CHARLES C. MEUTSCH. [L.S.]

Witnesses:

JNO. G. ELLIOTT,
ALICE OTTREY.
